DESIGN FOR A COAT

Philip Graber, New York, N. Y.

Application May 22, 1945, Serial No. 119,662

Term of patent 3½ years

(Cl. D3—4)

To all whom it may concern:

Be it known that I, Philip Graber, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my design,

Fig. 2 is the rear view of the coat shown in Fig. 1, on a reduced scale, and

Fig. 3 is fragmentary view of the coat shown in Fig. 1, illustrating the adjustable fur shawl revers in folded under and extended position.

The characteristic features of my design reside in the portions shown on the drawing in full lines.

I claim:

The ornamental design for a coat, substantially as shown and described.

PHILIP GRABER.
